UNITED STATES PATENT OFFICE.

JOHN W. HUTCHISON, OF BLACKWELL, OKLAHOMA TERRITORY.

COMBINED FENCE STRETCHER AND POST.

SPECIFICATION forming part of Letters Patent No. 769,479, dated September 6, 1904.

Application filed November 27, 1903. Serial No. 182,926. (No model.)

To all whom it may concern:

Be it known that I, JOHN W. HUTCHISON, a citizen of the United States, residing at Blackwell, in the county of Kay and Territory of Oklahoma, have invented certain new and useful Improvements in a Combined Fence Stretcher and Post, of which the following is a specification.

My invention relates to combined fence stretchers and posts, and is designed more especially as an improvement on a wire-fence stretcher on which Patent No. 573,150 was issued to me on December 15, 1896.

My particular object in this connection is to provide means for not only stretching the fence vertically, but also and with the same structure for bracing it laterally, so as to provide a fence which will successfully resist the efforts at escape of stock of all kinds.

A further object is to provide a post which in slightly-modified forms is adapted for use as a "corner-post," as a "division-post," or as an "outside post" and which can be easily and quickly set up or taken down.

With these and other objects in view the invention consists in certain novel and peculiar features of construction and organization, as hereinafter described and claimed, and in order that it may be fully understood reference is to be had to the accompanying drawings, in which—

Figure 1 represents a perspective view of a portion of a wire fence equipped with combined fence stretchers and posts embodying my invention, said figure showing a corner-post and a division-post. Fig. 2 is a horizontal section taken on the line II II of Fig. 1. Fig. 3 is a vertical section taken through the fence and ground contiguous to a combined fence stretcher and post, said figure showing the latter as an outside post.

Referring now to the drawings in detail, 1 designates the base or sill, the same for a corner-post being in the form of intersecting arms, whereas for division and outside posts it consists simply in a single arm. For the division-posts said arm is preferably of the same length as the arms of the corner-post sill, while for the outside post the sill is of shorter length, as shown in Fig. 3. In all

cases the sill is preferably of cast-iron or other suitable metal, and the ends of the arm or arms are formed with depending portions 2 for embedment in the ground, so as to serve as an anchor against dislocation or creepage 55 of the posts. The sills are provided at their upper sides with suitably-spaced lugs 3, the corner-post sill being provided centrally with four of said lugs, while the division and outside post sills are provided with only two of 60 said lugs. In the division-post sill the lugs are disposed near its center. In the outside-post sill they are preferably disposed near the inner end of the sill.

4 and 5 designate the two superposed members of the stretcher proper, said stretcher in the division and outside fence-posts constituting a part of the post. These members combined slightly exceed the height of the fence when stretched and have their contiguous ends hinged together, as at 6, and their opposite ends provided with grooves 7 to receive the top and bottom wires of the fence. For the corner-post structure the post 8 constitutes the locking-plate for the stretchers, 75 of which there are two, while in the other post structures a short plate 8^a constitutes the locking-plate. One member, 5, of each stretcher of the division and outside posts is secured permanently, as at 9, to the plate 8^a, while the other member, 4, is secured detachably, as by screw 10, to said plate, and said plates hold the two members in vertical alinement, so as to constitute a rigid structure. A pair of stretchers are provided for the corner-post 8, 85 a stretcher at each outer side thereof, and one member, 5, of each stretcher is secured permanently, as at 9^a, to the post, while the other member of each stretcher is detachably secured to the post, as by screws 10, the post 90 acting as a lock to hold the stretcher members vertical and rigid.

11 represents inclined braces, which are preferably of steel of suitable dimensions, having their upper ends bent vertically, as at 12, so to fit flatly against and be bolted to the top of the post 8, while the lower ends of said braces are bent inwardly to provide foot portions 13 to rest upon and be bolted to the outer ends of sills 1. For the division-posts 100

similar braces 11^a are provided, their upper ends being bent to a vertical position to fit flatly against and be bolted to the upper member of the stretcher, while their lower ends 5 are bent inward to form foot portions 13^a to rest upon and be bolted to the sill. For the outside post a similar brace 11^a unites the upper member of the stretcher to the end of the sill most remote from lugs 3.

10 In practice the fence, preferably of woven wire and consisting of horizontal or strand wires 14 and vertical or tie wires 15, is stretched as follows: The sill is first disposed at the point where the corner of the fence is to be 15 located, substantially as shown in Fig. 1. The post 8 is then mounted thereon, as shown, and braced with the fence-wire in contact with two of its sides. The stretchers while flexed or bent outward from the post on hinges 6 in an obvious manner have their upper grooves 7 engaged with the upper strand-wire, while their lower grooves 7 are engaged with the bottom strand-wire. The stretchers are then straightened out, so as to stretch the fence vertically, and 20 are then bodily lowered until their lower members and the post fit in the socket in the groundsill, being then secured, as at 9^a and 10^a, to the post 8, so as to secure them reliably in the position described. The fence 25 30 being then stretched longitudinally, the division and outside posts are set up. They are first placed adjacent to the fence at proper intervals in knockdown condition—that is, with the sills extending transversely of and 35 below the fence and the braces and stretchers disconnected from each other and from said sill, the stretchers being also in a flexed condition, as shown by dotted lines, Fig. 3, so as to bring their grooved ends nearer together 40 for engagement with the top and bottom strand-wires. After the depending ends of the sills are embedded in the ground to anchor them the stretchers are straightened to vertical position to stretch the fence and are 45 so secured by means of the locking-plates, the lower end of the stretchers being of course fitted between the lugs 3 of the sills before the members of the stretcher are locked together in vertical alinement by means of said 50 plates. The braces are now bolted to the upper members of the stretchers and to the sills, as shown and hereinbefore explained. For the outside post a single brace only at the outside of the fence is employed, as shown 55 in Fig. 3. A fence thus equipped with combined stretchers and posts of the type described is stronger and more durable than an ordinary post-fence and can be erected or taken down in less time and with less labor, 60 owing to the fact that no post-holes are needed in the erection and because the depending ends of the sills can be easily and quickly withdrawn from the ground without the necessity of any digging.

65 An ordinary post-fence offers comparatively

little resistance to the lateral pressure imposed upon the fence by the stock; nor does it usually hold the fence stretched sufficiently to prevent hogs from raising the lower wire or wires and escaping from below. With 70 this structure the fence is braced laterally from top to bottom and stretched so tightly in a vertical direction that there is practically no chance for a hog to escape below it. Lateral pressure against the fence is effectually 75 resisted by the inclined braces at the opposite side, and all the strain imposed upon any particular wire is through the medium of the stretcher distributed more equally upon all of the wires than in an ordinary post-fence, 80 and where the inclined braces are provided at both sides the attempt of a steer to uproot the post by hooking his horns under the inner inclined brace is resisted by the inclined brace and groundsill at the opposite side of 85 the fence.

This combined stretcher and fence-post possesses another advantage over the ordinary fence-post—namely, it can be removed temporarily when it is desired to burn dry weeds 90 or thistles where they have accumulated adjacent to or against the fence—a great many fences being destroyed in the western country by the employees of railroad companies, who when the weeds are dry frequently burn them 95 out along the railroad-tracks to avoid more serious conflagrations due to accidental ignition of said weeds by sparks from the locomotives. Furthermore, ranchmen frequently have occasion to burn up the immense amount 100 of thistles which accumulate against fences so heavily at times as to break them down and the only remedy is to burn them. My stretcher and post, as above stated, if made of wood may be easily and quickly removed preliminary to this burning operation and can 105 subsequently be replaced with the same ease and despatch.

If the combined fence stretchers and posts are made of metal, they will last a lifetime, corrosion being prevented by giving them at suitable intervals a coat of paint. The stretchers and posts also possess the desirable feature of simplicity, cheapness of construction, and lightness of weight, to the end that in knockdown condition they may be conveniently transported from one place to another.

From the above description it will be apparent that I have produced a combined stretcher and post for wire fences of any type which 110 includes connections between the horizontal wires so that the upward pressure on the top wire and the downward pressure on the bottom wire will stretch vertically the entire fence.

Having thus described the invention, what 115 I claim as new, and desire to secure by Letters Patent, is—

1. A combined fence stretcher and post, comprising a stretcher composed of a plurality of members connected together and adapted to 120

engage and stretch the fence vertically, means for locking said members in the relation they occupy while the fence is stretched, a groundsill connected to the stretcher near its lower 5 end, and an inclined brace connecting the groundsill with the upper part of the stretcher.

2. A combined fence stretcher and post, comprising a stretcher composed of a plurality of members connected together and adapted to 10 engage and stretch the fence vertically, means for locking said members in the relation they occupy while the fence is stretched, a groundsill connected to the stretcher near its lower 15 end and provided with depending portions embedded in the ground, and an inclined brace connecting the groundsill with the upper part of the stretcher.

3. A combined fence stretcher and post, comprising a stretcher composed of members 20 hinged together and adapted to be brought into vertical alinement and vertically stretch the fence, means to lock said members in vertical alinement, a groundsill projecting from the lower end of the lower section, and an inclined brace connecting the upper section with the groundsill.

4. A combined fence stretcher and post, comprising a stretcher composed of members hinged together and provided with a notch in 30 the lower end of the lower member to engage the bottom wire, and a notch in the upper end of the upper member to engage the top wire, a locking-plate to secure said members in vertical alinement, a groundsill connected 35 to the lower member, and an inclined brace connected at its opposite ends to the upper member and outer end of said groundsill.

5. A combined fence stretcher and post, comprising a stretcher composed of members 40 hinged together and provided with a notch in the lower end of the lower member to engage the bottom wire of the fence, and a notch in the upper end of the upper member to engage the top wire, a locking-plate to secure said

members in vertical alinement, a groundsill 45 connected to the lower member, an inclined brace connected at its opposite ends to the upper member and outer end of said groundsill, and portions depending from the groundsill and embedded in the ground.

50

6. A combined fence stretcher and post, comprising a stretcher composed of a plurality of members connected together and adapted to engage and stretch the fence vertically, 55 means for locking said members in the relation they occupy while the fence is stretched, a groundsill connected to the stretcher near its lower end and projecting from opposite sides of the fence, and inclined braces connecting the groundsill with the upper part of 60 the stretcher.

7. A combined fence stretcher and post, comprising a stretcher composed of a plurality of members connected together and adapted to engage and stretch the fence vertically, 65 means for locking said members in the relation they occupy while the fence is stretched, a groundsill connected to the stretcher near its lower end and projecting from opposite sides of the fence, inclined braces connecting 70 the groundsill with the upper part of the stretcher, and portions depending from the groundsill and embedded in the ground.

8. A combined fence stretcher and post, comprising a stretcher composed of members 75 hinged together, a locking-plate by which said members may be secured in vertical alinement, a groundsill provided with lugs forming a socket to receive the lower end of the stretcher, and inclined braces secured at their upper ends 80 to the upper portion of the stretcher and at their lower ends to said groundsill.

In testimony whereof I affix my signature in the presence of two witnesses.

JOHN W. HUTCHISON.
